(57) **CLAIM**

The ornamental design for a mobile terminal display screen with a graphical user interface, as shown and described.

DESCRIPTION

FIG. 1 is a front elevation view of a first image of a mobile terminal display screen with a graphical user interface according to a first embodiment;

FIG. 2 is a front elevation view of a second image thereof;

FIG. 3 is a front elevation view of a third image thereof;

FIG. 4 is a front elevation view of a fourth image thereof;

FIG. 5 is a front elevation view of a first image of a mobile terminal display screen with a graphical user interface according to a second embodiment;

FIG. 6 is a front elevation view of a second image thereof;

FIG. 7 is a front elevation view of a third image thereof;

FIG. 8 is a front elevation view of a fourth image thereof;

FIG. 9 is a front elevation view of a first image of a mobile terminal display screen with a graphical user interface according to a third embodiment;

FIG. 10 is a front elevation view of a second image thereof;

FIG. 11 is a front elevation view of a third image thereof;

FIG. 12 is a front elevation view of a fourth image thereof;

FIG. 13 is a front elevation view of a first image of a mobile terminal display screen with a graphical user interface according to an fourth embodiment;

FIG. 14 is a front elevation view of a second image thereof;

FIG. 15 is a front elevation view of a third image thereof; and,

FIG. 16 is a front elevation view of a fourth image thereof.

The appearance of the animated images sequentially transitions between the images shown in FIGS. 1-4, 5-8, 9-12, and 13-16. The process or period in which one image transitions to another forms no part of the claimed design. The dashed

(Continued)

lines and broken text and graphics represent unclaimed features that form no part of the claimed design. The dash-dot lines indicate the boundary of the mobile terminal display screen.

1 Claim, 16 Drawing Sheets
